UNITED STATES PATENT OFFICE

HAROLD PROTHERS, OF MILWAUKEE, WISCONSIN, ASSIGNOR TO VORCLONE COMPANY,
OF MILWAUKEE, WISCONSIN, A CORPORATION OF WISCONSIN

DOOR FOR WASHER DRUMS

Application filed December 15, 1927, Serial No. 240,136. Renewed August 29, 1929.

This invention relates to improvements in doors for washer drums.

Work with washer doors is rendered less dangerous in proportion to the extent to 5 which the washers may be kept tightly closed against leakage of liquid or vapor. It is the purpose of the present invention to provide a novel and improved type washer door formed to provide an internal lap joint with 10 the washer drum and to minimize the possibility of leakage without destroying the ease of opening and closing the door.

In the drawings:

Figure 1 shows a transverse section through 15 a washer embodying this invention.

Figure 2 is a detail in front elevation of a fragment of the device showing the door partially open.

Like parts are identified by the same reference characters in both views.

The washer drum 5 is of usual construction with the exception that the door opening may now be placed considerably lower through the use of the present invention than has 25 heretofore been possible. The obvious purpose in lowering the door is to facilitate the introduction and removal of heavy materials from the washers. Difficulties heretofore experienced with leakage have made it necessary to have the washer doors relatively high.

The usual legs for supporting the drum are shown at 6, the cylinder is illustrated at 30 7 and an arm shown at 8 provides a door stop at 9 and a pulley guide at 10 for the counter-balance rope 11 which, after passing around another pulley at 12 carries a weight 13.

The washer door 15 is provided at 16 with a hinge of the nature of a piano hinge upon 35 which the door may pivot for movement to its open position. It will be noted, however, that at its lower margin, door 15 is provided with a deep channel 18, one flange of which laps the interior of the drum 5 along the margin of the door opening. An angle mem-

ber at 19 reinforcing said margin immediately below the door opening serves as a seat for the channel portion 18 of the door and also tends to deflect any surges of liquid which might otherwise tend to escape between the lapped door and the drum.

The fact that the door 15 overlaps interiorly the margin of the drum apparently makes it impossible to open the door. This difficulty is overcome by an arrangement which permits the door to move bodily upwardly for a distance sufficient to disengage the door from the interior surface of the drum. To this end the jamb portion 20 of the washer drum to which the door is hinged, is itself hinged at 21 for a limited oscillatory movement with respect to the remainder of drum 5. An effective limitation of the movement of jamb 20 is provided for by extending axially the pintle 22 of hinge 16 and providing anchorage loops at 25 secured at 26 to the washer frame.

The counter-balance rope 11 is secured to an intermediate portion of door 15 as indicated at 27 and consequently serves to assist the operator in the initial bodily movement of the door as well as in the subsequent oscillatory movement thereof.

In operation, the door will normally be in the closed position indicated in the full lines in Figure 1 with its channeled lower margin engaging the margin of the door opening in the drum and at rest upon the angle iron seat 19. It will be obvious that very little liquid or vapor can escape from the door in view of the effective interior overlap thus provided.

When it is desired to introduce or remove articles from the washer, the operator grasps the door by means of its handle 28 and, assisted by the counterweight 13, readily lifts the door bodily to the extent permitted by the anchorage loops 25. In this initial lifting movement the door will retain approximately its original angular position, this being made possible by the oscillation of the jamb mem-

ber 20. At the conclusion of this bodily movement of the door, the parts will appear as shown in full lines in Figure 2 and in dotted lines in Figure 1.

5 It is only necessary for the operator to continue to thrust upwardly on the door to cause the door to oscillate to its uplifted dotted line position which is also shown in Figure 1, in which the door abuts stop 9. The counter-
10 weight continues to assist in this opening movement.

When it is desired to close the door, the counter-weight will insure that the hinged jamb 20 retains its elevated position until
15 the door has reached a position such as to require only the hinged movement of jamb 20 to accomplish its ultimate closure. If no counter-weight were provided, or if the point of application of the counter-weight were
20 changed, it might be difficult to manipulate the operation of the hinged jamb 20. In the device illustrated, however, the door acts in its hinged closing movement like a lever of the first class in that it has a tendency to oscillate
25 about the point 27 at which the counter-weight is attached and, to the extent to which this tendency exists, the force exerted to close the door maintains pintle 22 in its elevated position. It is only when the door is pulled
30 bodily downwardly in the final closing movement that the jamb 20 oscillates downwardly to the full line position of Figure 1.

It is, of course, understood that a spring would be fully equivalent for the counter-
35 weight shown. Hence reference to this feature in the appended claims will be understood to be generic.

I claim:

1. The combination with a drum provided
40 with a door opening, of a hinged door interiorly overlapping substantially continuously the margin of said opening in liquid tight relation thereto, and means for affording clearance between said door and said margin preliminary to the hinged opening movement of said door.

2. In a device of the character described, the combination with a drum having a hinged door jamb mounted for limited oscillatory
50 movement of its free margin, of a door hinged to said margin and formed to overlap interiorly a portion of said drum.

3. The combination with a drum having a door opening and provided with a hinged
55 door connecting portion, of a door hinged to the free margin of said portion and formed to overlap interiorly the lower margin of said opening and a counter-weight connected with an intermediate portion of said door where-
60 by to facilitate the bodily movement of said door with said drum portion and the independent hinged movement of said door.

4. In a device of the character described, the combination with a drum having a hinged
65 portion provided with a pintle at its free

margin, of a door for said drum hinged to said pintle and a counter-weight connected with an intermediate portion of said door.

5. In a device of the character described, the combination with a drum having a hinged portion provided with a pintle at its free
70 margin, of a door for said drum hinged to said pintle, and a counter-weight connected with an intermediate portion of said door, said drum being provided with limiting means defining the extent of oscillation of said hinged drum portion.

6. In a device of the character described, the combination with a drum having a hinged portion provided with a pintle at its free
80 margin, of a door for said drum hinged to said pintle, and a counter-weight connected with an intermediate portion of said door, said drum being provided with limiting means defining the extent of oscillation of said hinged drum portion and comprising a loop within which said pintle is guided.

7. The combination of a drum provided with a door opening and an interior seat adjacent the lower margin thereof, of a jamb member in hinged connection with the top of said drum, a door in hinged connection with the free margin of said jamb member and provided with a portion adapted in one position of said jamb member to overlap interiorly the lower margin of the said door opening and in another position of said jamb member to clear said margin.

8. The combination of a drum provided with a door opening and an interior seat adjacent the lower margin thereof, of a jamb member in hinged connection with the top of said drum, a door in hinged connection with the free margin of said jamb member and provided with a portion adapted in one position of said jamb member to overlap interiorly the lower margin of the said door opening and in another position of said jamb member to clear said margin, a stop means limiting the oscillation of said jamb member beyond said last mentioned position and a counter-weight connected with an intermediate portion of said door whereby to assist in the hinged opening movement of said door and also in the lifting of said door with said jamb member toward said last mentioned position.

9. In a washer, the combination with a liquid-tight housing provided with a door opening, of a door having a hinged connecting section, said section being hingedly connected to the housing and movable to and from closed position upon said housing, and said door being movable to a closed position upon said housing to interiorly overlap the edge of said opening in substantially liquid-tight engagement therewith.

10. In a washer, the combination with a drum having a door opening close to the horizontal central plane of the drum, of a door

having a hinged connecting section, said section being hingedly connected to the housing and movable to and from closed position upon said drum, and said door being slidably movable in the course of relative movement between said door and section to and from a position in which its lower margin overlaps the lower edge of said opening in substantially liquid-tight relation.
